DESIGN FOR A PHOTOGRAPH RECEIVING PLAQUE OR SIMILAR ARTICLE

Norbert Lenz, Cleveland, Ohio, assignor to Lyra
R. Haber, doing business as Wonder Products
Co., Cleveland, Ohio

Application November 24, 1942, Serial No. 108,861

Term of patent 7 years

To all whom it may concern:

Be it known that I, Norbert Lenz, a citizen of the United States and a resident of Cleveland, in the county of Cuyahoga and State of Ohio, have invented a new, original, and ornamental Design for a Photograph Receiving Plaque or Similar Article, of which the following is a specification, reference being had to the accompanying drawing, forming a part thereof.

In said drawing, Fig. 1 is a front elevational view of a photograph receiving plaque or similar article showing my new design; and Fig. 2 is a side elevational view thereof. The dominant features of the design reside in those portions thereof shown in full lines.

I claim:

The ornamental design for a photograph receiving plaque or similar article, as shown and described.

NORBERT LENZ.
